US00D995171S

(12) **United States Design Patent** (10) Patent No.: **US D995,171 S**
(45) Date of Patent: **** Aug. 15, 2023**

(54) **RETAIL FIXTURE**

- (71) Applicant: **Apple Inc.**, Cupertino, CA (US)
- (72) Inventors: **Allison Inouye**, San Francisco, CA (US); **Jean-Marc Gady**, Los Altos, CA (US); **Ismael Flores Trujano**, San Jose, CA (US); **Gregory Guillaume Lespinard**, San Jose, CA (US); **Mi Zou**, San Francisco, CA (US); **Po Huang**, San Jose, CA (US); **Wesley Bryan Hamm**, San Francisco, CA (US); **Russell John Kaaihue Heirakuji**, Cupertino, CA (US); **Joshua Robert Edwards**, Santa Cruz, CA (US); **Nicholas E. Corti**, San Francisco, CA (US); **Manuel Dejesus**, San Francisco, CA (US); **Alice Marlin Brugger**, San Francisco, CA (US)
- (73) Assignee: **Apple Inc.**, Cupertino, CA (US)
- (**) Term: **15 Years**
- (21) Appl. No.: **29/849,845**
- (22) Filed: **Aug. 15, 2022**

Related U.S. Application Data

- (63) Continuation of application No. 29/807,410, filed on Sep. 10, 2021, now Pat. No. Des. 960,616, which is a continuation of application No. 29/763,378, filed on Dec. 22, 2020, now Pat. No. Des. 930,409, which is a continuation of application No. 29/713,511, filed on Nov. 15, 2019, now Pat. No. Des. 906,026.

(57) **CLAIM**

The ornamental design for a retail fixture, as shown and described.

DESCRIPTION

FIG. 1 is a top front perspective view of a retail fixture showing the claimed design;
FIG. 2 is a front view thereof;
FIG. 3 is a rear view thereof;
FIG. 4 is a left side view thereof;
FIG. 5 is a right side view thereof
FIG. 6 is a top view thereof;
FIG. 7 is a bottom view thereof;
FIG. 8 is a top front perspective view of another retail fixture showing the claimed design;
FIG. 9 is a front view thereof;
FIG. 10 is a rear view thereof
FIG. 11 is a left side view thereof;
FIG. 12 is a right side view thereof;
FIG. 13 is a top view thereof; and,
FIG. 14 is a bottom view thereof.
The dashed broken lines in the figures show portions of the retail fixture that form no part of the claimed design.
The dot-dash broken lines in the figures show boundaries that form no part of the claimed design.

1 Claim, 10 Drawing Sheets
